UNITED STATES PATENT OFFICE.

RICHARD K. LE BLOND AND WILLIAM F. GROENE, OF CINCINNATI, OHIO, ASSIGNEES
TO THE R. K. LE BLOND MACHINE TOOL COMPANY, OF CINCINNATI, OHIO, A COR-
PORATION OF OHIO.

RELIEVING ATTACHMENT FOR LATHES.

980,975.

Specification of Letters Patent. Patented Jan. 10, 1911.

Application filed March 28, 1910. Serial No. 552,001.

To all whom it may concern:

Be it known that we, RICHARD K. LE BLOND and WILLIAM F. GROENE, citizens of the United States, and residents of Cincinnati, Ohio, have invented certain new and useful Improvements in Relieving Attachments for Lathes, of which the following is a full, clear, and exact specification.

This invention pertains to certain new and useful improvements in lathes, and relates more particularly to an attachment for turning a relief or clearance on the teeth of taps and milling cutters, and other work which requires clearance to the radial face 15 of the tooth, such as gear cutters, forming cutters, &c.

The invention has for its object to provide mechanism to be attached to the compound rest of a lathe and to be driven by the spindle of the latter, whereby a reciprocating motion is given to the top slide of 20 said compound rest.

A further object is to provide improved means for varying the number of reciprocations per revolution of the work.

A further object is to provide means to relieve at any angle to which the top slide may be swiveled.

A further object is to provide for the 30 adjustment of the top slide at all times whether the relieving attachment is engaged or not.

The invention will be hereinafter fully set forth and particularly pointed out in 35 the claims.

In the accompanying drawings, wherein similar letters of reference are used to indicate corresponding parts in each of the several views: Figure 1 is a side view of a 40 portion of a lathe illustrating our invention; Fig. 2 is a longitudinal sectional view illustrating the compound rest; Fig. 3 is a cross section on line 3—3, Fig. 2; Fig. 4 is a similar view on line 4—4, Fig. 2; Fig. 5 is a detail view illustrating the change speed 45 gearing; and Fig. 6 is a detail of the operating shaft for the relieving mechanism.

Referring to the drawings A designates the drive gear mounted on the end of the 50 spindle, a quadrant a being supported by a bracket a' and carrying selectable change gears a , a' that connect with the spindle gear. Said gearing is arranged to transmit

motion to a telescopic shaft B provided with knuckle joints b and operatively connected with the driving shaft b' . The shaft B, by reason of its flexible and telescopic construction provides a flexible connection between the bracket a' and the compound rest C so that the latter may be adjusted in and out and also along the carriage. The shaft b' is journaled in the swivel slide b^2 and carries a cam b^3 , the rise on which is made to correspond to the amount of relief required on the work.

The compound rest is provided with a sliding piece D, disposed between the top slide d and the swivel slide b^2 , which carries at the lower end, the stud d' and roller d^2 . At the upper end it is connected to the cross feed screw d^3 of the compound rest C. This construction admits cross adjustment of the top slide at all times. A coil spring d^4 acts against the piece D, in such a manner as to keep the cam b^3 against roller d^2 , 75 and furnishes the means for returning the top slide to relieve the next tooth in the work.

In use, the attachment operates as follows: Motion is transmitted from the spindle gear A through the selectable change gears a^2 and a^3 at the end of the lathe to the telescopic shafts B and the shaft b' in the swivel slide b^2 of the compound rest, to which the cam b^3 is attached, giving said cam continuous rotating motion in definite relation to the spindle. As the cam revolves against the roller d^2 the piece D is driven forward, since the piece D is connected to the top slide d of the compound rest by means of a cross feed screw d^3 , the reciprocating motion of the slide D is directly transmitted to the top slide d which carries the operating tool. As soon as the point of the cam clears the roller the spring d^4 acting against the piece D returns the slide d and piece D to position. 90

When the functions of the relieving attachment are not required, the piece D is locked securely in position by drawing the nuts d^5 on bolt d^6 which being rigidly connected to the piece D as by screw threads, brings said piece D, and the swivel slide d^2 together, locking these two members to form an absolutely rigid construction, and holding the roller d^2 out of engagement with cam b^3 . 105

It will be understood, of course, that the number of reciprocations per revolution of the work is dependent upon the number of teeth in the cutter or tap, and these proportions can be varied by means of selectable change gears at the end of the lathe. It will be further noted that by means of our improved relieving mechanism the compound rest top slide can be swiveled at any angle, thereby admitting of the cutters being relieved on their side faces.

What we claim as new and desire to secure by Letters Patent is:—

1. The combination with a compound tool rest of a lathe provided with a top slide and a swivel slide, of a sliding piece disposed between said slides, a driving shaft having one end extended transversely through said swivel slide, a spring carried by said swivel slide and acting against said sliding piece, and a cam carried by said shaft for moving said sliding piece against the action of said spring and means for locking said sliding piece against movement relative to said swivel slide, and to also hold said sliding piece out of engagement with said cam.
2. The combination with the compound tool rest of a lathe provided with a top slide and a swivel slide, of a sliding piece disposed between said slides, a driving shaft having one end extended transversely through said swivel slide, a spring carried by said swivel slide and acting against said sliding piece, and a cam carried by said shaft for moving said sliding piece against the action of said spring, a bolt rigidly connected to said sliding piece, and nuts working on said bolt and adapted to prevent rel-

ative movement of said sliding piece and said swivel slide.

3. The combination with the compound tool rest of a lathe, provided with a top slide and a swivel slide, of a sliding piece disposed between said slides and operatively connected with the top slide, and means for periodically reciprocating said sliding piece, and means for locking said sliding piece against movement relative to said swivel slide, and to also hold said sliding piece out of engagement with said reciprocating means.

4. The combination with a compound tool rest of a lathe provided with a top slide and a swivel slide, of a sliding piece mounted on said swivel slide, means for connecting said sliding piece with said top slide, a cam supported by said swivel slide, a rod secured to said sliding piece and extended through said swivel slide, a spring carried by said swivel slide and encircling said rod said spring acting on said sliding piece to hold the same in engagement with said cam, and means for rotating said cam, and nuts on the end of said rod, whereby relative movement of said sliding piece and swivel slide is prevented when the nuts are tightened.

In testimony whereof we have signed our names to the specification in the presence of two witnesses.

RICHARD K. LE BLOND.
WILLIAM F. GROENE.
